(57) **CLAIM**

We claim the ornamental design for chair backrest and seat, as shown and described.

DESCRIPTION

FIG. 1 is a front perspective view of a chair backrest and seat of the invention. The view from the opposite side being a mirror image thereof.

FIG. 2 is a side view of a chair backrest and seat of the invention. The view from the opposite side being an identical mirror image thereof.

FIG. 3 is a front elevational view of a chair backrest and seat of the invention.

FIG. 4 is a rear elevational view of a chair backrest and seat of the invention; and,

FIG. 5 is a top plan view of a chair backrest and seat of the invention.

The portions of the figures shown in dashed lines are for illustrative purposes only and form no part of the claimed invention.

1 Claim, 5 Drawing Sheets# US D661,133 S
